UNITED STATES PATENT OFFICE.

CHARLES ROWLAND, OF QUINCY, ILLINOIS.

CALCULATING DEVICE.

SPECIFICATION forming part of Letters Patent No. 284,576, dated September 4, 1883.

Application filed July 16, 1883. (No model.)

To all whom it may concern:

Be it known that I, CHARLES ROWLAND, of Quincy, in the county of Adams and State of Illinois, have invented a new and useful Improvement in Calculating Devices; and I do hereby declare that the following is a full and exact description of the same, reference being had to the accompanying drawings, and to the letters of reference marked thereon.

10 My invention relates to that class of devices known as "calculating devices;" and the object I have in view is to provide a simple and convenient device of this character by means of which the fundamental rules of arithmetic—as addition, subtraction, multiplication, and division—may be taught with great facility, and the learner enabled by its use to become thoroughly conversant with the table of each rule in a comparatively short period of time.

15 With these ends in view the invention consists in the features of construction and the arrangement and adaptation of parts, as will be more fully hereinafter set forth, and specifically pointed out in the claims.

20 To enable others to understand how to construct and operate my device, I will now proceed to describe the same with reference to the accompanying drawings, which form a part of this specification, and in which—

25 Figure 1 is a plan view of the reverse side of the device, showing the arrangement and adaptation of parts for multiplying numbers. Fig. 2 is a similar view of the obverse side, showing the adaptation of parts for dividing numbers. Fig. 3 is a plan view of the reverse side of the device, showing the adaptation of parts when designed for adding numbers; and Fig. 4 is a similar view of the obverse side, showing the arrangement of parts when designed for subtracting numbers.

30 Similar letters of reference denote like parts throughout all the views.

In the drawings, A represents a circular plate or disk, which is provided with a bifurcated handle, B, the bifurcated parts, as b, extending to the center of the disk, at which point the latter is pivotally secured thereto, and thereby adapted to be rotated between said parts b as occasion requires in operating the device.

35 C and C' represent the reverse and obverse sides, respectively, of the disk. The surface

of each side is divided into thirty-six equal parts by means of the radial lines a, said lines extending from the periphery of the disk to 55 points equidistant from its center. Then by means of curved lines the inner ends of the radial lines are connected in such manner as to have three of the said lines connected, and then, leaving the contiguous lines unconnected, 60 have the three next lines connected, and so on in that order for the entire number of lines. The spaces within the connected lines a are then subdivided into twelve equal parts or spaces by means of curved lines drawn parallel with 65 the curved lines that connect the inner ends of the said lines a. The curved lines are represented by the letter a' in the drawings.

70 From the above description, taken in connection with the drawings, it will be observed that the faces or sides of the disk are each provided with a series of twelve similar groups of lines, each group comprising three of the radial lines a and twelve of the curved lines a', and being divided thereby into two radial 75 columns of twelve transverse spaces each.

75 It will be further observed that between each group of the lines a and a' there is a radial space, (represented by letter D,) in which no lines a' appear.

80 The outer surfaces of the parts b of handle B are divided by a series of transverse lines into twelve spaces, said spaces corresponding in width to those formed by curved lines a', so that by rotating disk A until any one of 85 the radial spaces D is covered by the part b the lines and spaces upon its surface and those formed by the curved lines a', contiguous therewith, may coincide. The spaces upon the handle are numbered from one to twelve, 90 beginning with the space nearest the center of the disk and ending with the last space near its periphery.

95 For adapting the device to multiplying numbers, the reverse side C of the disk is provided with the arrangement of figures as shown in Fig. 1 of the drawings. By consulting said figure, it will be seen that the numbers to be multiplied are arranged in the spaces of the radial columns at the left of the 100 radial spaces D, said numbers running, respectively, from one to twelve around the face of the disk from left to right, while in the spaces of the radial columns at the right of

said spaces D are arranged the numbers representing the respective products of those numbers when multiplied by the figures upon handle B. The table is completed by printing the word "is" above the line of products of the number 1, the word "are" above the products of the other lines of numbers, and the word "times" above the number on handle B.

For adapting the device to dividing numbers, the figures are arranged as shown in Fig. 2 of the drawings. Here the numbers to be divided occupy the spaces of the radial columns at the left of the radial spaces D, and the dividing numbers or divisors the spaces of the radial columns to the left of these columns, while the quotient, or the number of times one set of figures is contained in the other, is represented, respectively, by the numbers upon handle B. With this distinction the arrangement of the figures is the same as that for multiplying. The table is completed by printing word "into" above the lines of numbers to be divided, and word "times" above the numbers on handle B.

For adding numbers, the figures are arranged as shown in Fig. 3 of the drawings. Here the numbers to be added, with their respective amounts, are arranged in substantially the same manner as in the table for multiplying, while the numbers on handle B represent the numbers which are added to the figures in the radial columns at the left side of spaces D. The table is completed by printing word "make" above each line of amounts, and word "and" above the figures on handle B.

For subtracting numbers, the figures are arranged as shown in Fig. 4 of the drawings. Here the numbers to be subtracted are arranged in substantially the same manner as in the table for dividing, while the numbers on the handle represent, respectively, the difference between any two sets of figures in the radial columns at the left of radial spaces D, heretofore referred to. The table is completed by printing word "from" above the radial columns just to the left of spaces D, and the word "leaves" above the figures on handle B.

The operation of the device is as follows: If it is desired to use the multiplication table and to find any one of the twelve tables—as, for instance, the table of fives—the device is held by handle B and the disk A rotated until the column of fives is just at the left of the numbers upon the handle, and the part b of the latter occupies the radial space D, and is thus brought between the numbers to be multiplied and their products. If it is desired to use the division-table, the disk is rotated until the handle occupies the radial space to the right of the columns of numbers which it is desired to divide, the figures upon the handle in this instance showing the number of times the respective divisor is contained in the number desired to be divided.

In the addition and subtraction tables the

operations of the device are substantially the same as for multiplying and dividing, respectively.

While I prefer to make the calculating device in sets of two each, so that one will serve for adding and subtracting numbers and the other for multiplying and dividing, yet, if desired, the same might be made in sets of four, with only one table represented on the rotating disk. In the latter case the face of the disk on which no table appears might be provided with any suitable ornamental or other representation.

It will be apparent that many slight alterations as to the details of form and construction may be resorted to without departing from my invention. For instance, the rotating disk might be secured to the handle by means of a spring or clamp pivot, so as to allow ready removal therefrom, and thus the one handle be utilized for the whole number of disks in a set. Again, the lines by which the disk and handle are divided into the number-containing spaces might be omitted, and only the numbers with which calculations are to be made appear, their relative arrangement upon the disk and handle of course being the same as in the first instance. Again, the periphery of the disk might be flanged, and its reverse and obverse faces provided with removable paper or card-board plates, upon which appear the desired lines and numbers for any one of the tables. Again, the disk and handle might be divided into more than twelve number-containing spaces, and thus the device be adapted to make calculations with numbers of higher denominations. Hence I do not limit myself to the precise construction shown and described, but reserve to myself the right to make all such changes and alterations as may properly fall within the scope of my invention.

Having thus described my invention, what I claim is—

1. In a device for calculating numbers, the combination, with a circular disk having upon its reverse side a series of radial spaces, with radial columns to the left and right of the radial spaces, the columns at the left containing the numbers with which calculations are to be made, and those at the right the numbers representing, respectively, the results of such calculations, of a handle provided with bifurcated parts, between which the disk is centrally pivoted, and having a column of figures arranged, as shown, for making calculations with the columns of numbers at the left of any of the radial spaces upon the disk, accordingly as the latter is rotated to bring said numbers and figures in juxtaposition, all substantially as set forth.

2. In a device for calculating numbers, the combination, with a circular disk having upon its obverse side a series of radial spaces, with two radial columns at the left of the radial spaces, the columns containing, respectively, the numbers with and by which calculations are to be made, of a handle provided with bi-

furcated parts, between which the disk is centrally pivoted, and having a column of figures arranged, as shown, for representing the results, respectively, of the calculations between the said columns of numbers at the left of any of the radial spaces upon the disk, accordingly as the latter is rotated to bring said numbers and figures in juxtaposition, all substantially as set forth.

10 3. In a device for calculating numbers, the combination, with a circular disk having upon its reverse side a series of radial spaces, with radial columns to the left and right of the radial spaces, the columns at the left containing the numbers with which calculations are to be made, and those at the right the numbers representing, respectively, the results of the calculations, and having a similar series of radial spaces upon its obverse side, with two radial 15 columns at the left of said radial spaces, the columns containing, respectively, the numbers with and by which calculations are to be made,

of a handle provided with bifurcated parts, between which the disk is centrally pivoted, and having upon its reverse and obverse sides a 25 similar column of figures, arranged as shown, the figures upon the reverse side being designed for making calculations with the columns of numbers at the left of any the radial spaces upon the reverse side of the disk, and those 30 upon the obverse side of the handle for representing the results, respectively, of the calculations between the columns of numbers at the left of any the radial spaces upon the obverse side of said disk, accordingly as the latter is 35 rotated to bring said numbers and figures in juxtaposition, all substantially as set forth.

This specification signed and witnessed this 16th day of July, 1883.

CHARLES ROWLAND.
